UNITED STATES PATENT OFFICE.

EDWIN CALDWELL, OF NEW YORK, N. Y.

DESIGN FOR A COMBINED CIGARETTE AND MATCH RECEPTACLE.

Application filed February 12, 1924. Serial No. 8,619. Term of patent 3½ years.

To all whom it may concern:

Be it known that I, EDWIN CALDWELL, a citizen of the United States, and a resident of the city of New York, in the borough of Manhattan and State of New York, have invented a new, original, and ornamental Design for Combined Cigarette and Match Receptacle, of which the following is a specification, reference being had to the accompanying drawings, forming part hereof.

The figure is a perspective view of the article, showing my new design.

I claim:

The ornamental design for a combined cigarette and match receptacle, as shown.

EDWIN CALDWELL.
